SUCTION CLEANER

Charles H. Taylor, North Canton, Ohio, assignor
to The Hoover Company, North Canton, Ohio,
a corporation of Ohio

Application January 2, 1935, Serial No. 185

5 Claims. (Cl. 21—127)

The present invention relates to suction cleaners in general and particularly to an odorizer unit in a suction cleaner construction. More specifically the invention comprises a new and novel odorizer unit adapted to form a part of a suction cleaner unit and which includes manually operable valve means which open a volatile element to a stream of air or which seal it therefrom.

10 It is an object of the present invention to provide a new and improved odor-creating means in a suction cleaner. Another object of the invention is to provide an odorizer unit in which the volatile element is positioned within a moving air stream, valve means being provided to open the volatile element to the air stream or seal it therefrom. Still another object is the provision of an odorizer accessory which is adapted to be connected to a dusting tool hose through which a stream of air is forced, the accessory unit including a volatile element. Still another object is the provision, in a suction cleaner, of an accessory which is adapted to be removably secured to the outer end of a dusting tool hose and which includes a removable vial 15 of a volatile agent which is adapted to be connected to or sealed from a stream of moving air by manually operable valve means. These and other more specific objects will appear upon reading the following specification and claims and upon considering in connection therewith the drawing to which they relate.

Referring now to the drawing in which a preferred embodiment of the invention is disclosed:

35 Fig. 1 is a side elevation of a modern suction cleaner unit embodying the present invention;

Fig. 2 is an enlarged showing of the accessory comprising the present invention connected to the end of the cleaner dusting tool hose;

40 Fig. 3 is a section upon the line 3—3 of Fig. 2;

Fig. 4 is a transverse cross section through the unit showing the manually operable valve, being taken upon the line 4—4 of Fig. 3;

Fig. 5 is a section through the unit showing the 45 removable vial positioned therein;

Fig. 6 is a section upon the line 6—6 of Fig. 3;

Fig. 7 is a section upon the line 7—7 of Fig. 3.

A preferred embodiment of the invention is disclosed in the drawing, and in Fig. 1 in particular, a modern suction cleaner is illustrated. The cleaner nozzle 1 is connected to the fan chamber 2 through an air passageway 3, which may be formed as a removable element in a manner well known in the art. The fan chamber 55 is provided with an exhaust outlet 4, to which

is attached, in the normal operation of the machine in on-the-floor cleaning, a removable dust bag of an ordinary type. In the use of the present invention, however, the dust bag is removed from the cleaner, and to the exhaust outlet 4 is 5 attached a dusting tool hose 5, at the outer end of which is removably secured the odorizer unit 6. A motor casing 7 is positioned above the fan chamber 2 and encloses an unshown driving motor of any common type, preferably a universal 10 motor, which drives the suction-creating fan 8 positioned within the chamber 2. The cleaner is supported upon front and rear wheels 9 and 10 and a pivoted handle 11 is provided by which the operator can exert the necessary force to 15 propel the machine in its operation.

The dusting tool hose 5 is secured to the cleaner exhaust outlet 4 by any suitable means such as a manually operable nut 12 and is formed at its outer end with a channelled metallic seat 20 member 13. Seat member 13 is adapted to receive and seat any one of a plurality of dusting tool cleaning elements or accessories. The odorizer unit 6 is connected directly to the metallic seat 13. 25

The odorizer unit 6 comprises a hollow cylindrical metallic body 14 which is flared outwardly at its outer end and which is of such size at its inner end that it is adapted to enclose and seat upon metallic seat 13 of the hose 5. A spring-pressed detent 15, of a common and well known type, extends through the body 14, being positioned upon the outer surface thereof, and its inner end seats within the channel of the metallic seat 13 where it functions to prevent unintentional separation of the unit and the hose. 35 Adjacent the portion of the unit body carrying the detent 15 the body is enlarged in diameter and there is positioned therein a cylindrical mounting member 16 which is spaced from 40 the body 14, except at its points of support, and is secured thereto by screws 17, 17, 17. The outer end of support 16, which is cylindrical in shape, is open while the inner closed end is formed with a reduced 45 collared opening 18. Within the support 16 and spaced from the collared inner end thereof is a dividing wall 19 which is formed near its center with ports 20, 20 etc., and at a greater radial distance from its center with ports 21, 21 etc. 50 The plate is formed with arcuate cutout sectors around its periphery so that the chambers which it forms in the mounting member are in fact connected.

Rotatably mounted within the collared opening 55

18 is the central hollow body portion of a valve 22 which is formed with a central projecting portion which extends through a central opening in plate 19 and has its edge peened over to prevent 5 separation. The valve is formed as a circular flange adjacent the plate 19 and this portion of the valve contacts the plate and extends outwardly beyond the outer ring of ports 21, 21 etc. in that member. Valve 22 is rotatable in its seat 10 and is provided with central ports 23, 23 etc. and ports 24, 24 etc. at a greater radial distance from the axis of rotation. The central valve ports 23, 23 etc. extend from the hollow central portion of the valve, which opens toward the inlet or dust 15 ing tool hose end of the unit, to the wall 19. The outer ports 24, 24 etc. of the valve extend through the flanged portion of the valve and from the plate 19 into the cylinder 16. In one rotary position of the valve the central ports 23, 23 etc. and 20 the outer ports 24 mate with the inner ports 20, 20 etc. and the outer ports 21, 21 etc. respectively, of the stationary plate 19.

The valve 22 is rotatable between definite limits by a manually operable lever 25, which extends 25 outwardly through a slot 26 in the body 14. The lever carries a closure plate 27 which closes all parts of the slot 26, except that part closed by the lever 25 itself, to prevent passage of air therethrough. The inner end of lever 25 encircles the 30 central body portion of valve 22 in fixed relationship and is secured thereto by a nut 28 which seats in screw threaded relationship upon the outer screw threaded surface of the valve body.

A volatile-agent-containing vial 29 is positioned 35 within the cylinder 16 in spaced relationship thereto being supported by circumferentially spaced leaf springs 30, 30, 30 which contact its outer surface. The receptacle or vial is formed with an open end which faces the wall or plate 40 19, being spaced therefrom by a ring gasket 31 which is preferably of a resilient material, such as felt or rubber. The vial 29 contains a volatile agent or element which is of any preferred type such as a cake or a liquid saturating a body of 45 wick material. The volatile element or its carrying wick preferably does not extend entirely to the open end of the receptacle 29 but is spaced slightly therefrom, as is clearly indicated in Figure 3 of the drawing.

Vial 29 is held against outward displacement 50 from the unit by means of a pivoted cap or plate 32, positioned at the open flared end of the body 14 and normally retained in its vial-securing position by means of a manually operable spring latch 55 33. The inner face of the plate 32 is provided with spaced inwardly extending springs 34, 34 which contact the outer end of vial 29 to urge it against the sealing gasket 31 at its open end.

In the operation of this preferred form of the 60 invention the closing of the motor switch causes the suction-creating means to operate and air under pressure to be exhausted from the cleaner into the dusting tool hose 5. Clean air is exhausted from the machine and passes through 65 the hose and into the body 14 of the odorizer unit. With the lever 25 pivoted to one of its end positions, that indicated by the word "Off" in Figure 2, no air passes into contact with the volatile element and all air exhausted passes around the cylinder 16 which functions as the mounting means. 70 With the valve moved to its opposite end position, that marked by the word "On" in Figure 2, air is forced under pressure through the hollow central body portion of valve 22, through the aligned ports 23, 23 and 20, 20 of the valve and the plate

19, respectively, and into contact with the volatile element exposed at the mouth of the vial. This air passes over the volatile element and escapes into cylinder 16 through the aligned ports 21 and 24 which are at a greater radial distance from the 5 center of the valve. The odor-bearing air is forced rearwardly past the plate 19 and down the length of the cylindrical mounting member 16 to join, at the open end of the unit, the air which has passed around the vial-carrying member. All of the air is exhausted from the flared end of the unit at the sides of cap 32 and may be directed to any desired point by pointing the unit 10 in the direction desired.

Upon the volatile agent within the vial becoming exhausted it is only necessary for the operator to pivot the closure plate 32 to permit of the manual removal of the vial and the insertion of a new vial in its place. The presence of the manually controllable valve insures that unintended 20 volatilization of the volatile element will not take place when the unit is not in use.

I claim:

1. In an odorizer unit, a body formed with an inlet adapted to be connected to a source of air 25 flow and with an exhaust outlet, a closed body of volatile element normally closed to atmosphere and air flowing through said body, means to convey a part only of the air flowing through said body into contact with said element, means to 30 convey said air from said element, said means including valve means to open said element to said air or to seal it therefrom.

2. In an accessory for a suction cleaner, a hollow body open at its ends, a receptacle for a 35 volatile element having a single open end, means removably seating said receptacle in said body, valve means to direct a part only of an air stream passing through said body into and from said receptacle or to seal said receptacle completely 40 from said air.

3. In an odorizer accessory for a suction cleaner, a hollow body having inlet and outlet openings, said inlet opening being adapted to be connected to a source of air flow, a receptacle for 45 a volatile element formed with an opening at one end only, means mounting said receptacle in spaced relationship to said body with said opening facing the flow of air and dividing said opening into air inlet and air outlet openings, and 50 single valve means including a manually operable lever extended outwardly through said body to open or close the openings of said receptacle.

4. An odorizer unit for a suction cleaner comprising a hollow body having an inlet and an outlet, said body being adapted to serve as a passageway for an air stream, a container, a volatile element in said container, means to guide air from said inlet into said container and over the surface of said element, means to guide air from said 60 container in the direction of said outlet, and means to open and close said container to both said means.

5. An odorizer unit for a suction cleaner comprising a hollow cylindrical body having an air 65 inlet and an air outlet, manually operable means at the air inlet end to secure said body to a source of air, a vial-seat in said body between its ends, a vial seated with its single open end in said seat, air passageways arranged to connect the open end 70 of said vial to direct air into and from said body, said passageways including manually operable valve means, and a pivoted closure member at the air outlet to secure said vial to said seat.
